UNITED STATES PATENT OFFICE.

THOMAS C. WARNER, OF WICHITA, KANSAS.

SCHOOL-DESK.

1,361,422.

Specification of Letters Patent.

Patented Dec. 7, 1920.

Application filed July 13, 1920. Serial No. 395,915.

To all whom it may concern:

Be it known that I, THOMAS C. WARNER, a citizen of the United States, residing at Wichita, in the county of Sedgwick and State of Kansas, have invented new and useful Improvements in School-Desks, of which the following is a specification.

This invention relates to furniture, particularly to school desks, and has for its object the provision of a desk which has its top portion so hinged as to prevent the leaving of any cracks when it is raised, the advantage being that it is impossible for a child using the desk to catch his fingers and pinch them.

Another object is the provision of a desk in which the receptacle for books and other articles is carried rigidly by the top, this entire structure being capable of being swung upwardly out of obstructing relation to the seat so that the seat may be easily taken or left.

Another object is the provision of a desk of this character which is so constructed that the angular inclination of the top portion may be varied to a certain extent.

An additional object is the provision of a desk of this character which will be simple and inexpensive in manufacture, efficient in use, durable in service, and a general improvement in the art.

With the above and other objects and advantages in view, the invention consists in the details of construction to be hereinafter more fully described and claimed and illustrated in the accompanying drawings in which—

Figure 1 is a side elevation of the desk in normal position,

Fig. 2 is a front elevation thereof,

Fig. 3 is a plan view, and

Fig. 4 is a side elevation with the top portion shown in section and swung upwardly.

Referring more particularly to the drawings, the numeral 10 designates broadly a chair structure including a seat 11, a back 12, and an arm 13 located at one side, preferably the right. This arm extends an appreciable distance beyond the front of the seat and is secured at its forward end to an upright post 14. A brace bar 15 is connected with the post below the level of the seat and is also connected with the adjacent front leg of the chair structure.

The post 14 extends upwardly beyond the arm 13 and has secured upon its upper end a transverse bar 16 which is cylindrical in shape with a flattened bottom. An ornamental grille 17 is secured to the post 14 and bar 16 and serves as a brace. The numeral 18 designates a brace bracket which is secured to the arm 13 and to the grille 17.

The numeral 19 designates the movable portion of the desk as a whole and this movable portion comprises a substantially rectangular top 20 having secured upon its underside a box-like receptacle 21 for books, papers, and the like, and this receptacle has its end or side toward the chair open. Secured upon the side edges of the top 20 are arms 22 which are pivoted, as shown at 23, upon the ends of the bar 16.

In order to limit upward swinging movement of this movable portion I provide plates 24 secured upon the ends of the bars 16 and over which the arms 22 move. These plates are formed with outwardly extending lugs 25 which are engaged by the arms 22 when the movable portion is swung upwardly to its maximum extent.

The bottom 26 of the book receptacle is prolonged toward the front, that is toward the grille 17 and carries a bolt or set screw 27, the head of which engages against the grille and forms a stop for limiting downward movement of the movable portion. By screwing this bolt in or out, it will be apparent that the inclination of the movable portion when in normal position, may be varied to a certain extent.

From the foregoing description and a study of the drawings it will be apparent that if desired the entire movable portion 19 may be swung upwardly out of obstructing relation to the chair so that the pupil 95 may get into or leave the seat very easily and that catching his clothing upon the desk structure is avoided. A very important feature, it will be noted, is the fact that there are no cracks within which a finger 100 may be caught and pinched when the movable portion is swung in either direction.

It is of course to be observed that any suitable pencil or pen rack 29 and ink bottle holder 28 may be provided in the top of 105 the bar 16.

While I have shown and described the preferred embodiment of my invention, it is of

course to be understood that I reserve the right to make such changes in the form, construction, and arrangement of parts as will not depart from the spirit of the invention or the scope of the subjoined claims.

Having thus described my invention, I claim:

1. A device of the character described comprising a chair structure including an arm 10 extending forwardly beyond the edge of the seat, a vertical support secured to the forward end of said arm, a transverse cylindrical bar carried by the top of said support, a desk proper including a top and an open 15 ended box-like receptacle secured upon the underside thereof, and arms secured to the side edges of said top and pivoted upon the ends of said bar, the hinged edge of the top being very close to the periphery of the

transverse bar at all times to prevent the 20 formation of an appreciable crack.

2. A device of the character described comprising a chair structure including an arm 25 extending forwardly beyond the edge of the seat, a vertical support secured to the forward end of said arm, a transverse bar carried by the top of said support, plates secured upon the ends of said bar, a desk proper including a top and an open ended 30 box-like receptacle secured upon the underside thereof, arms secured to the edges of said top and pivoted upon said plates, and lugs formed on said plates and engageable by said arms for limiting upward swinging movement of said desk structure. 35

In testimony whereof I affix my signature.

THOMAS C. WARNER.
